Primary Examiner—Ruth McInroy

[57] CLAIM

An ornamental design for a removable oven bottom drip pan, as shown and described.

DESCRIPTION

FIG. 1 is a perspective view of a removable oven bottom drip pan showing my new design, the details shown in broken lines are for illustrative purposes only and form no part of the claimed design;

FIG. 2 is a perspective view thereof;

FIG. 3 is a top plan view thereof;

FIG. 4 is a front elevation view thereof, the rear view being identical;

FIG. 5 is a bottom plan view thereof; and,

FIG. 6 is a right side elevation view thereof, the left side being a mirror image thereof.
